UNITED STATES PATENT OFFICE.

GEORGE P. FARMER, OF MONT CLAIR, NEW JERSEY.

IMPROVEMENT IN BUTTON-CARDS.

Specification forming part of Letters Patent No. 222,482, dated December 9, 1879; application filed November 10, 1879.

To all whom it may concern:

Be it known that I, GEORGE P. FARMER, of Mont Clair, Essex county, New Jersey, have invented a new and useful Improvement in Button-Cards, of which the following is a specification.

My invention relates to that class of button-cards in which a number of small cards, each carrying a dozen or any other determinate number of buttons, are attached to a strip of pasteboard; and the main object of my invention is to afford facilities for readily affixing the smaller cards to and detaching them from the said strip.

In the accompanying drawings, Figure 1 represents a plan view of part of a button-card drawn to an enlarged scale; Fig. 2, an edge view of Fig. 1; Fig. 3, a section of the card, and Fig. 4 a perspective view of the device for attaching the smaller to the larger cards.

A is a strip of pasteboard or other suitable material forming the main card, to which are attached any desired number of smaller cards, B, and to each of the latter are attached twelve buttons, a. I usually attach twelve of the smaller cards to the strip A, so that the latter will display a gross of buttons.

It is important that the smaller cards should admit of being readily detached from the main strip by the retailers for purchasers. For this purpose I provide each of the small cards with two flexible metallic tongues, d d, projecting from the back of the card, as shown in Fig. 2. These tongues are arranged to pass through

slits in the main strip, and are bent at the back of the same, as shown in Fig. 3, so that when a small card has to be detached all that is necessary is to so bend the tongues that they can be readily withdrawn from the main strip. The tongues form part of a plate, D, Fig. 4, in the body of which are two holes, e e, so arranged in respect to the two central buttons of the card that in stitching the former to the latter the stitches will pass through the said openings, the plate D being thus confined between the buttons and the card, through slits in which the tongues d d of the plate project.

I usually cover each of the small cards before the buttons are stitched to the same with tin-foil, f, which conceals the body of the plate D.

I claim as my invention—

1. A button-card in which a number of small cards, B, each carrying a number of buttons, and having at the back elastic metallic tongues d d, are combined with a strip, A, having slits for receiving the said tongues, all substantially as set forth.

2. The combination of the plate D, having tongues d d and openings e e, with the card B and its buttons, as set forth.

In testimony whereof I have signed my name to this specification in the presence of two subscribing witnesses.

GEORGE P. FARMER.
